UNITED STATES PATENT OFFICE.

FRED W. COOLEY, OF MINNEAPOLIS, MINNESOTA.

REINFORCED-CONCRETE BIN STRUCTURE.

1,098,559.

Specification of Letters Patent.

Patented June 2, 1914.

Application filed November 18, 1911. Serial No. 660,956.

To all whom it may concern:

Be it known that I, FRED W. COOLEY, a citizen of the United States, residing at Minneapolis, in the county of Hennepin and State of Minnesota, have invented certain new and useful Improvements in Reinforced-Concrete Bin Structures; and I do hereby declare the following to be a full, clear, and exact description of the invention, 10 such as will enable others skilled in the art to which it appertains to make and use the same.

My invention has for its object to provide an improved metal reinforced concrete 15 structure especially adapted for use as a country elevator, and to such ends, generally stated, the invention consists of the novel devices, combinations of devices and arrangement of parts hereinafter described 20 and defined in the claims.

The invention is capable of many modifications, but in the drawings, the preferred arrangement thereof, designed for use as a country elevator, is illustrated.

25 In the drawings, like characters indicate like parts throughout the several views.

Referring to the drawings, Figure 1 is an elevation showing the complete elevator; Fig. 2 is a horizontal section taken approximately on the line $x^2 x^2$ on Fig. 1; Fig. 3 is a vertical section taken approximately on the line $x^3 x^3$ on Fig. 2; and Fig. 4 is a horizontal section taken on the line $x^4 x^4$ on Fig. 3.

35 The elevator structure shown, includes four main outside or corner bins 1, and a multiplicity of intermediate square bins 2. The walls of all of which bins are of monolithic concrete reinforced with embedded 40 metallic rods or bars 3 in the said walls. The walls of the main bins 1 extend from the foundation upward, while the walls of the square bins 2 are terminated at a sufficient elevation to afford a work room 4. 45 One of the square bins 2, is utilized as the main lift well, and the elevator leg 5 is extended therethrough, and through the working room 4 and down into the pit 6 and up into the cupola 7. The other square bins 2 50 are provided with the usual hopper bottoms. At its upper end, the elevator leg 5 delivers to a loading spout 8 of the usual or any suitable construction. The pit 6 extends partly under the working room 4 and 55 partly under the tilting platform 9 of a dumping scale of usual or any suitable con-

struction, and which is located in a weighing and dumping shed 10, located adjacent to an office and engine room 11. The walls of all of the compartments of this structure are, 60 as already indicated, constructed from concrete, reinforced more or less with metallic rods. The walls of the cupola 7 are formed by extending upward the walls of certain of the square bins 2.

65 The salient feature of this invention resides in the novel arrangement of the walls of the main bins in respect to each other, and usually also in respect to the walls of the square or rectangular intermediate bins.

70 In the preferred arrangement illustrated in the drawings, the walls of the main bins 1 are cylindrical or circular in cross-section throughout 270 degrees or three-quadrants of their circumference, and for the intermediate 90 degrees, or quadrant of the bins, they are formed with walls that extend tangentially from the curved walls of the bins and join each other at a right angle, and constitute, in most instances, also walls of 75 certain of the rectangular bins. By reference, particularly, to Fig. 4, it will be noted that the straight wall sections of the main corner bins 1 are alined with, or formed as extensions of certain of the intermediate 80 walls of the rectangular bins, and the metallic reinforcements 3, follow an endless course through the curve and straight walls of the said main bins and through the alined straight walls of the intermediate rectangular bins. This brings the circular or curved 85 main bins and rectangular intermediate bins into the most compact form possible, absolutely eliminating waste space, and at the same time affording a structure in which 90 the walls of the different bins, mostly, contribute to brace each other. In this further 95 respect, it should be noted that the extreme outer walls of the intermediate rectangular bins extend between the curved walls of the 100 main outer or curved corner bins approximately on lines intersecting the axes thereof, and thus afford struts and tie members in the said curved bins. Also, this novel arrangement of the bins gives a very attractive contour and neat appearance to the finished structure.

105 In connection with the dumping scale platform 9, I provide a novel wagon guiding device which, as shown, comprises a long guide rail 12, a short guide rail 13, and a platform 14 having oblique rods or bars.

The platform 14 extends level with and outward from the dumping platform 9. The long guide rail 12 is rigidly anchored and extends from a point at one side of the 5 inner end portion of the dumping platform 9, on an outwardly diverging line to a point at or near but offset from the front or outer end portion of the platform 14. The short 10 guide rail 13 extends forward a short distance from the rail of the side portion of the platform 9 and is anchored at the opposite side from the rail 12. With this arrangement, a wagon may be driven on a driveway 15 in the direction of the arrow 15 marked thereon in Fig. 2, until the rear end thereof is passed over the outer end of the rail 12, and then the wagon may be backed up onto the platform 9, and as it is backed, the wheels thereof will be caused to drift 20 sidewise, both by the guide rail 12 and by the oblique bars of the platform 14, and in this way, the wagon wheels will be directed onto said platform.

In Fig. 3, a portion of a car 16 is shown on 25 the track at one side of the elevator, in position to receive grain from the loading spout 8.

What I claim is:

1. A structure of the kind described, made up of main and intermediate bins, the 30 said main bins having curved walls throughout three quadrants thereof, and having straight walls in the fourth quadrant, that meet at a right angle and form the sides of different intermediate bins. 35

2. A structure of the kind described made up of main and intermediate bins, the said main bins having curved walls throughout three quadrants thereof and having straight walls in the fourth quadrant extended at 40 ninety degrees to each other, and the said intermediate bins having walls in rectangular arrangement, certain of which are alined and joined with the straight wall sections of the said main bins and having their bottoms spaced above the lower ends of said main bins. 45

In testimony whereof I affix my signature in presence of two witnesses.

FRED W. COOLEY.

Witnesses:

F. D. MERCHANT,
HARRY D. KILGORE.
